UNITED STATES PATENT OFFICE.

HAROLD A. WILLS, OF PLAINFIELD, NEW JERSEY.

RAILROAD CROSSTIE.

Application filed March 19, 1928. Serial No. 262,631.

The invention relates to an improvement in railroad cross-ties.

In spite of persistent efforts to find a satisfactory substitute wood has remained thus far the best material for railroad cross-ties. It is strong enough for the purpose and above all it possesses the necessary resiliency. The serious drawback with wood is that it is not durable and wear resistant and the growing scarcity of timber results in the mounting cost of woods suitable for railroad cross-ties. Hence the effort is still continued to find a satisfactory substitute for wood. It has been proposed to use concrete, but concrete alone does not possess the necessary resiliency and its stone-like nature prevents the use of ordinary spikes for holding the rails on the cross-ties. For this reason it has been proposed to combine concrete and metal with wood inserts for the spikes. For one reason or another, however, combination concrete and steel cross-ties as heretofore proposed and used have not been entirely satisfactory, and wood still continues to be the chief reliance of the railroads for cross-ties. The object of the present invention is to produce an improved railroad cross-tie in which wood, concrete and steel are so combined as to give the necessary resiliency, afford the spikes a proper holding material to be driven into, and which will be durable in service and cheaper to maintain than cross-ties composed wholly of wood. To these ends the invention consists in the improved railroad cross-tie herein-after fully described and particularly pointed out in the appended claims.

In the accompanying drawings illustrating the preferred form of the invention, Fig. 1 is a top plan of the improved railroad cross-tie; Fig. 2 is a side elevation of the tie shown in Fig. 1; Fig. 3 is a longitudinal section through the improved cross-tie and taken on the line 3—3 of Fig. 1; Figs. 4 and 5 are cross-sections taken on the lines 4—4 and 5—5, respectively, of Fig. 1; Fig. 6 is a side elevation showing, disassembled, the parts composing the improved cross-tie; Fig. 7 is a side elevation of a modified form of the improved railroad cross-tie; Fig. 8 is a top plan of the tie shown in Fig. 7; and Fig. 9 is a side elevation showing the modified form of tie disassembled.

The improved railroad cross-tie illustrated in Figs. 1 to 6, comprises two blocks or base pieces 10 and 11 composed of reinforced concrete. Each block 10 and 11 is an elongated

member somewhat rectangular in cross-section but slightly wider at its base 12 than at its top 13, as shown in Fig. 4. The block 10 is adapted to be placed under one and the block 11 under the other of two opposite rails. Preferably the blocks are so arranged that they extend on either side of the rails substantially equal distances to afford a proper distribution of the weight on the bottom surfaces 12 of the blocks.

The blocks 10 and 11 are held in alinement with each other under the rails by means of a tie-piece 15 composed of steel or other appropriate metal. The tie-piece 15 is a flat elongated member and at its ends is received in shallow recesses 16 formed in the top surface of the inner ends of the base block. The recesses 16 are of such depth that when the ends of the tie-piece are received therein the top surface of the tie-piece is substantially flush with the top surface 13 of the base blocks. In order to strengthen and protect the tie-piece 15 and also to hold the base blocks 10 and 11 at a fixed distance apart to assist in preserving the gauge of the railway the tie-piece 15 is embedded in a concrete alinement member 17 the lower part 18 of which is somewhat wedge-shaped and abuts at each end against the adjacent inner surfaces 19 of the base blocks. The outer ends 20 of the upper part of the member 17 project endwise beyond the lower wedge-shaped portion 18 and rest upon the upper surfaces 13 of the inner ends of the base blocks. It is thus clear that the member 17 serves to protect and strengthen the tie-piece 15 and also acts as an alinement member for the base blocks.

To afford a proper cushion for the rails resting on the base blocks 10 and 11, I provide wear pieces 21 composed of wood. Each wear piece is substantially rectangular in form and rests on the middle part of the upper surface of its base block. In depth or thickness each wooden wear piece 21 is substantially equal to the height of the part of the member 17 projecting upwardly from the top surfaces of the base blocks, thereby providing a substantially plane surface for the top of the cross-tie. At their inner ends the wear pieces 21 abut against the outer ends 20 of the member 17 and at their outer ends the wear pieces 21 abut against the shoulders 22 formed on the outer ends of the upper surfaces of the base blocks. The parts thus far described are held together to constitute a cross-tie by means of the bolts 23, the lower

ends of which are received in appropriate recesses or holes formed in the concrete base blocks 10 and 11, as clearly indicated in the drawings. The outer ends of the metal tie-piece 15 are provided with holes through which pass the inner pair of bolts 24.

On the upper edge of the front side of each base block is formed a shoulder 25 against which abuts the front edge or side of the wear pieces 21. I designate as "front" that part of the base blocks and wear pieces which is facing in the direction of travel of the trains and hence the direction of movement or "creep" of the rails under the action of the trains. The shoulders 25 prevent the wear pieces 21 from shifting under the action or creep of the rails. The other edge of the upper surface of the base blocks is left free in order that wear pieces of different widths may be used without trimming them to a particular dimension, thus saving considerable time and labor in road repairs, and also in the cost of the wear pieces. Superposed on substantially the middle portion of each wear piece is a metal tie plate 26 provided with an outer shoulder 27 adapted to engage with the outer edge of the rail. Holes 28 are provided in each tie plate to receive the spikes which hold the rail on the tie plate and in place on the cross-piece. The spikes pass downwardly through the wear pieces 21 and into wooden blocks 29 sunk in the upper surface of the base blocks.

It will be recognized by those particularly skilled in this art that the improved cross-tie described above possesses the advantages of an all wood tie as to resiliency and also the advantages of a combined concrete-metal tie as to strength and durability. The concrete base blocks 10 and 11 are easily shifted and for this purpose the dog holes 30 are provided in the upper edges of their lateral sides. When the wear pieces are worn out they can be easily and quickly replaced by sliding them laterally over the top surfaces of the base blocks without moving the latter, the absence of a shoulder on the upper edges of the rear sides of the base blocks permitting this mode of operation.

In the modified form of the improved cross-tie shown in Figs. 7, 8 and 9 the concrete insert or alinement member 32 is considerably shortened and the inner ends of the base blocks 33 and 34 correspondingly lengthened. The metal tie-piece 35 is also shortened and the wooden wear pieces 36 lengthened. This modified form of cross-tie is especially intended to prevent damage to the alinement

member of the cross-tie in the event of derailment. In the modified form of cross-tie, in order to secure an equal distribution of weight on the lower surfaces of the ends of the base blocks 33 and 34 projecting laterally beyond each side of the rails, while maintaining the tie plates 37 substantially in the middle of the blocks 33 and 34, I have widened the outer ends of the blocks and narrowed the inner ends thereof, as shown in Fig. 8. In other respects the modified form of cross-tie is exactly the same as the preferred form and functions in the same manner.

Having thus described the invention what I claim as new is:—

1. A railroad cross-tie comprising, two concrete base blocks having on the upper surfaces of their inner ends shallow recesses, a metal tie-piece received at its ends in the recesses in the base blocks, a concrete alinement member in which the middle section of the metal tie-piece is embedded with its ends projecting longitudinally beyond the ends of the concrete alinement member, the ends of the upper part of the alinement member projecting laterally beyond the sides of the metal tie-piece to rest upon the upper edges of the inner ends of the base blocks, and the middle section of the alinement member projecting downwardly between the base blocks and abutting the inner ends thereof, and means for holding the parts of the cross-piece together.

2. A railroad cross-tie comprising, two concrete base blocks having on the upper surfaces of their inner ends shallow recesses, a metal tie-piece received at each end in the recesses in the base blocks, a concrete alinement member in which the middle section of the metal tie-piece is embedded with its ends projecting longitudinally beyond the ends of the concrete alinement member, the ends of the upper part of the alinement member projecting laterally beyond the sides of the metal tie-piece to rest upon the upper edges of the inner ends of the base blocks, and the middle section of the alinement member projecting downwardly between the base blocks and abutting the inner ends thereof, wooden wear pieces superposed upon the middle sections of the upper surfaces of the base blocks, the base blocks being provided with upwardly projecting shoulders engaging the wear pieces to prevent lateral displacement of wear pieces under the creep of the rails, and means for holding the parts of the cross-tie together.

HAROLD A. WILLS
